P. RADOCCHIO,
STREET INDICATOR FOR CARS,
APPLICATION FILED MAR. 20, 1914.

Patented Jan. 11, 1916.

UNITED STATES PATENT OFFICE.

PASQUALE RODOCCIO, OF PROVIDENCE, RHODE ISLAND, ASSIGNOR OF ONE-THIRD TO NICOLA DI DOMENICO, OF PROVIDENCE, RHODE ISLAND.

STREET-INDICATOR FOR CARS.

1,167,432.

Specification of Letters Patent. Patented Jan. 11, 1916.

Application filed March 20, 1914. Serial No. 826,103.

To all whom it may concern:

Be it known that I, PASQUALE RODOCCIO, a subject of the King of Italy, and residing in the city of Providence, in the county of Providence and State of Rhode Island, United States of America, have invented certain new and useful Improvements in Street-Indicators for Cars, of which the following is a specification.

10 This invention relates to street indicators for trolley cars and has for its object to provide a simple and effective mechanism whereby a ribbon is mounted to be wound from one roll to another and have painted upon 15 its face in spaced apart relation the name of the different streets of that route and to provide a motor which is energized by contact with members depending from the trolley wire to operate the ribbon rolls and 20 bring into view the name of the next street which the car is approaching.

A further object of the invention is to provide a solenoid as the motive power for operating the ribbon rolls whereby each 25 time the solenoid is energized a full stroke of the same moves the ribbon the required distance to bring into view another reading.

30 A further object of the invention is to provide means whereby the direction of movement of the ribbon may be readily reversed.

A further object of the invention is to provide means whereby ribbon rolls may be readily removed and another inserted in 35 its place as often as the car is changed from one route to another so as to properly indicate the different cross streets of that route.

With these and other objects in view, the 40 invention consists of certain novel features of construction, as will be more fully described and particularly pointed out in the appended claims.

In the accompanying drawing: Figure 1— is a side elevation showing a portion of 45 a street car in section with my improved street indicator device mounted at either end within the car and the trolley pole as provided with a contact to engage a corresponding contact depending from the trolley wire. Fig. 2— is a detail front view of the indicating mechanism, and the casing as partly 50 broken away. Fig. 3— is an end elevation illustrating the action of the solenoid on the ribbon rolls through the medium of the 55 main shaft. Fig. 4— is a detail showing the

front view of the trolley pole and wire and showing the two contacts in engagement one with the other. Fig. 5— is a diagrammatic view showing the wiring system. Fig. 6— is an end view of one of the centers showing 60 its flattened nose through which the rolls are driven.

Referring to the drawing, 10 designates the trolley wire from which is supported a contact member 11 at intervals along the 65 same, said contacts being usually placed midway between the cross streets of the route upon which the car is traveling, or at any other desired points along the trolley wire. On the usual trolley pole 14 I have 70 mounted an elongated arm 15 off set laterally therefrom, as illustrated in Fig. 4, so as to contact with the roll 12 of member 11 upon passing the same. In the car there is 75 mounted one of my improved street indicators in the casing 16. Each of said indicators is constructed with an upper roll 17 and a lower roll 18 on which rolls is wound a portion of ribbon, tape or sheet 19 of flexible material, such as cloth or the like, on the 80 face of which is preferably painted or otherwise imprinted the names of the streets of the route on which the car is traveling, said names being spaced apart on the ribbon so that but one will appear at a time in the 85 opening 20 of the casing 16. The roll 17 is supported at one end on the common lathe center 21 and at its opposite end by a flat nosed center 22, see Fig. 6, which center is 90 adapted to be pressed outward into engagement with a corresponding slot in the end of the roll by the action of a spring 23. At 18 is a lower roll onto which another portion of the ribbon is wound and between which rolls the ribbon is arranged to extend; this lower roll is retained in a similar manner to the upper roll, one end being 95 supported by the center 24, while the opposite end is supported on the flat nosed center 25 similar to that illustrated in Fig. 6 100 through which center this lower roll is driven, said center being pressed into engaging position by means of the coil spring 26 whereby when it is desired to remove this 105 particular roll or sheet of street indicating ribbon, it is only necessary to withdraw the centers 22 and 25 and the whole may be lifted out and another indicating the cross streets of the new route positioned in its place. In order to operatively support these 110

different centers and cause them to drive the rolls properly I have provided supporting standards 27 and 28 at opposite ends of said rolls, each standard having two oppositely extended arms, provided with openings near their ends, forming bearings in which said centers may rotate, and have also provided a main driving shaft 29 which extends from one frame across to the other. This shaft is provided at one end with the gears 30 and 31. The latter gear is driven by the former and runs loosely on the jack shaft 32 and is provided with a clutch member 33. A second clutch member 34 is mounted 15 to slide endwise on a key in the jack shaft and is arranged to be operated by the handle 62 so that a movement of the handle to the left causes the clutch members to engage and drive the center 25 and consequently 20 the roll carried by it. This center is mounted on a key to slide endwise in a socket in the end of this jack shaft so that it may be withdrawn for the purpose of releasing its roll.

25 In order to obtain a reverse winding motion of the ribbon it is found necessary to rotate the upper roll 17 in the opposite direction. To accomplish this I have mounted a gear 35 on the opposite end of the main shaft, which gear drives a gear 36 loosely mounted on the jack shaft 37 through an idler gear 38. A clutch member 39 is mounted on this jack shaft 37 to slide on a key therein. In order to operate both of 30 these clutches simultaneously so that one shall be thrown into engagement at the same time that another is thrown out, I have connected these clutches 34 and 39 by the rod 40 and both may be operated at once by a 35 single handle lever 62. This hand lever is provided with a tooth on its inner face adapted to work over the quadrant 41 which quadrant is provided with three recesses for the reception of this tooth, on the lever, 40 whereby when the tooth is in the recess at the right the clutch 39 is in engagement and the ribbon is moved upward, and when the lever is thrown to the left the tooth engages the recess at the left and the clutch 34 is 45 then in engagement, and clutch 39 out of engagement, in which case the ribbon is moving in a downward direction, and when it is desired that the ribbon shall move in neither direction even though the motor may be 50 operated, the lever 62 is moved to central position to engage the recess 43.

55 As an actuator for this mechanism I have preferably provided a motor in the form of a solenoid 44 as the simplest, most effective 50 and most direct means of obtaining the required results. To coöperate with this solenoid I have mounted a plate 45 on the end of the main shaft which plate is provided with a plurality of laterally extending pins 60 46, preferably four in number. I have also

provided a downwardly extending arm 47 on the solenoid, pivoted at 60 to the solenoid core, said arm having a laterally extending lip 48 near its lower end with a beveled head 49 below the lip. A guide pin 50 is positioned on one side of said arm 47 and a spring 51 to yieldably hold the arm against said guide 50, whereby when the solenoid is deenergized this arm drops by gravity or other suitable means, and the beveled end 75 49 rides over the next pin below and finally hooks beneath the same. As the solenoid is energized it rises during the engagement of the contacts 12 and 15 the full length of its stroke which moves the pin upward and rotates the main shaft 29 one-quarter revolution. As soon as the solenoid is deenergized it again drops to be in position for engagement with another pin when another engagement is made with the contact members 12 80 and 15 and the operation repeated. If desired a bell 52 may be employed for calling the attention of the passengers to the fact that another street is being approached and is being indicated. In order to operate this 85 bell a hammer 53 is pivotally mounted at 54, the opposite end of the hammer arm 55 is in position to be engaged by the pin 56 on the gear 31 as it rotates so that as the pin moves from the arm the hammer is carried upward by the spring 57 to engage and ring the bell.

90 The operation of my improved street indicating device may be further described as follows: As the contact members 12 and 15 100 on the trolley pole and wire are brought into engagement with each other during the travel of the car, just before a cross street is reached an electrical connection is made and the current passes through the wire 58 105 and energizes both solenoids 44 and 59 whereb^w both of the indicating devices are operated simultaneously to indicate to people at both ends of the car the name of the street next to be reached. As above described the mechanism may be operated through the movement of the lever 25 so that either the upper roll 17 will be actuated to roll the ribbon upward, or the roll 110 18 may be actuated to roll the ribbon downward, to correspond to the direction in which the car is traveling, and the order in 115 which the different streets will be reached.

One of the essential features of the invention is the readiness by which the different rolls may be removed from the mechanism and a fresh one mounted to take its place. This is of particular advantage when a car is required to run on different routes which is found in practice to be often the case. 120

125 I claim:

1. A street indicator of the character described, comprising spaced apart standards each having oppositely extended arms, the arms of each standard being parallel with 130

the arms of the other standard, spaced apart 5 rolls between said standards, a ribbon carried by said rolls, a rotatable center mounted in the end of an arm of one standard and engaging an end of one of said rolls, a second rotatable center mounted in the end of an arm of the other standard and engaging the opposite end of the other roll, jack shafts rotatably mounted in the ends of the remaining 10 arms of said standards and having sockets in their ends, spring pressed centers mounted in said sockets and engaging the ends of the respective rolls opposite those engaged by the first mentioned center, a motor, and means for simultaneously connecting either jack shaft with the motor when the other jack shaft is disconnected therefrom.

2. A street indicator of the character described, comprising spaced apart standards each having oppositely extended arms, the arms of each standard being parallel with the arms of the other standard, spaced apart rolls between said standards, a ribbon carried by said rolls, a rotatable center mounted in the end of an arm of one standard and engaging an end of one of said rolls, a second rotatable center mounted in the end of an arm of the other standard and engaging the opposite end of the other roll, jack shafts rotatably mounted in the ends of the remaining arms of said standards and having sockets in their ends, spring pressed centers mounted in said sockets and having 25 flat noses engaging the ends of the respective rolls opposite those engaged by the first mentioned centers, the ends of said rolls being grooved to receive said flat noses, a motor, and means for simultaneously connecting either jack shaft with the motor when the other jack shaft is disconnected therefrom.

3. A street indicator of the character described, comprising spaced apart standards each having oppositely extended arms, the arms of each standard being parallel with the arms of the other standard, each standard being also provided with a laterally disposed bearing midway between the arms thereof, a main shaft rotatably supported by said bearings, spaced apart rolls between said standards, a ribbon carried by said rolls, a rotatable center mounted in the end of an arm of one standard and engaging an end of one of said rolls, a second rotatable center mounted in the end of an arm of the other standard and engaging the opposite end of the other roll, jack shafts rotatably mounted in the ends of the remaining arms of said standards and having sockets in their ends, spring pressed centers mounted in said sockets and engaging the

ends of the respective rolls opposite those engaged by the first mentioned centers, and means for simultaneously connecting either 65 jack shaft with said main shaft when the other shaft is disconnected therefrom.

4. A street indicator of the character described, comprising spaced apart standards each having oppositely extended arms, the 70 arms of each standard being parallel with the arms of the other standard, spaced apart rolls between said standards, a ribbon carried by said rolls, a rotatable center mounted in the end of an arm of one standard and engaging an end of one of said rolls, a second rotatable center mounted in the end of an arm of the other standard and engaging the opposite end of the other roll, jack shafts rotatably mounted in the ends of the 75 remaining arms of said standards and having sockets in their ends, spring pressed centers mounted in said sockets and engaging the ends of the respective rolls opposite those engaged by the first mentioned centers, 80 a motor, a clutch lever pivotally supported by one of said standards, clutches for connecting said jack shafts with said motor, and means operated by said clutch lever for rendering each clutch inoperative as the 85 other is made operative.

5. A street indicator of the character described, comprising spaced apart standards each having oppositely extended arms, the arms of each standard being parallel with 95 the arms of the other standard, spaced apart rolls between said standards, a ribbon carried by said rolls, a rotatable center mounted in the end of an arm of one standard and engaging an end of one of said rolls, a second rotatable center mounted in the end of an arm of the other standard and engaging the opposite end of the other roll, jack shafts rotatably mounted in the ends of the 100 remaining arms of said standards and having sockets in their ends, spring pressed centers mounted in said sockets and engaging the ends of the respective rolls opposite those engaged by the first mentioned centers, a motor, a clutch lever pivotally supported by one of said standards, a guide carried by the other standard, a clutch member attached to said lever for connecting one of said jack shafts to the motor, a clutch rod attached to said lever and passed through 105 said guide, and a second clutch operated by said rod for connecting the other jack shaft with the motor.

In testimony whereof I affix my signature in presence of two witnesses.

PASQUALE RADOCCIO.
